(57) **CLAIM**

The ornamental design for a wireless charger, as shown and described.

DESCRIPTION

FIG. 1 is a front, top perspective view of a first embodiment of a wireless charger, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front, top perspective view of a second embodiment of the wireless charger;
FIG. 10 is a rear, bottom perspective view thereof;
FIG. 11 is a front elevation view thereof;
FIG. 12 is a rear elevation view thereof;
FIG. 13 is a left side elevation view thereof;
FIG. 14 is a right side elevation view thereof;
FIG. 15 is a top plan view thereof;
FIG. 16 is a bottom plan view thereof; and,
FIG. 17 is a cross sectional view taken along line 17 in FIG. 11.

The dash-dash broken lines in the drawings illustrate portions of the wireless charger that form no part of the claimed design. The dot-dash broken lines indicate the cross section and form no part of the claimed design. The cable is shown with a symbolic break in its length. The appearance of any portion between the break lines forms no part of the claimed design.
